WITNESS:

Gerald Kennedy, Jr.

UNITED STATES PATENT OFFICE.

FRED R. SIMON AND ALBERT A. SIMON, OF VERDON, NEBRASKA.

TRAP GUN.

Application filed May 25, 1925. Serial No. 32,781.

To all whom it may concern:

Be it known that we, FRED R. SIMON and ALBERT A. SIMON, citizens of the United States, residing at Verdon, in the county of Richardson and State of Nebraska, have invented new and useful Improvements in Trap Guns, of which the following is a specification.

This invention relates to a trap gun, the general object of the invention being to provide a gun for killing gophers and the like by placing the gun in the runways of the animals and by having the trigger mechanism of the gun actuated by dirt thrown thereon by an animal.

Another object of the invention is to provide means whereby a cartridge can be easily and quickly placed in the barrel of the gun.

Another object of the invention is to provide an adjustable supporting leg for the gun and also to provide means for adjusting a tension of the spring which actuates the hammer.

This invention also consists in certain other features of construction and in the combination and arrangement of the several parts, to be hereinafter fully described, illustrated in the accompanying drawings and specifically pointed out in the appended claims.

In describing our invention in detail, reference will be had to the accompanying drawings wherein like characters denote like or corresponding parts throughout the several views, and in which:

Figure 1 is a side view of the improved device.

Figure 2 is a section on line 2-2 of Figure 1.

Figure 3 is a view of the blank from which a part of the gun is formed.

Figure 4 is a view of the trigger plate.

Figure 5 is a view of the hammer.

In these views, 1 indicates a channel-shaped supporting member and 3 indicates a U-shaped bracket which is fastened to the rear part of said member. This bracket is formed from a blank such as that shown at

A in Figure 3, the wide portions of the blank being fastened to the side walls of the member 1 with the upper extensions *a* being curved at their upper ends and the curved parts fastened together to form a closed loop, as indicated at 4 in Figure 2. The bolt 5

which connects the bracket with the supporting member 1 and which has a spacing sleeve thereon, forms a support for the barrel 6 of the gun, which has its lower end supported by a bracket 7, which is pivotally supported in the lower part of the member 1 by means of the bolt 8. Thus the bracket can rock in the member 1 so that the gun barrel can be raised from a position where it rests on the bolt 5 to a position where it would strike the upper end of the loop 4. This latter position is the loading position, as shown in dotted lines in Figure 1. The hammer of the gun, as shown at 8", is pivoted in the member 1, as shown at 9. This hammer has its projection 10 arranged to strike the cap of the cartridge placed in the barrel when the barrel is in its lowest position. The teat on the hammer passes through a hole 3' made in the piece 3" which connects the two parts of the blank together. The hammer is thrown against the cartridge, when the trigger mechanism to be described, is actuated, by means of a spring 11 which is fastened to the hammer and to a bolt 12 which is adapted to be placed in any one of a number of pairs of holes 13 made in the member 1. These holes permit the tension of the spring to be adjusted. The trigger mechanism comprises a pedal-like member 14, pivoted to the lower end of member 1, as shown at 15, and having a roller 16 at its lower end which is adapted to engage a hook 17 formed on a rod 18 which is pivoted to the lower end of the hammer, as shown at 19. These parts are so formed that when the member 4 is depressed, it will release the hook 17 and thus free the rod 18 so that the spring 11 can pull the hammer forwardly against the cartridge to explode the same. A bolt 18' acts as a check to the upward movement of the rod 18. A yoke-shaped member 20 is pivoted to the rear end of the member 1, as shown at 21, to form a leg for the member. By tilting this leg, the device can be adjusted to the proper angle. Spacers 22 are placed on the various bolts and pivots for holding the walls of the member 1 apart.

This gun is placed in the runway or burrow of the animals after removing the dirt from a portion of the same. The gun is first turned upside down and then the hammer pulled back. The member 14 will drop under the action of gravity and catch the

hooked end of the rod 18 and thus hold the hammer in cocked position. The device is then turned right side up and its lower end pushed into the hole. It is then adjusted 5 by its leg 20 to train the barrel on the hole. The barrel is then raised, as shown in dotted lines in Figure 1, and a cartridge inserted, and then the barrel is pushed back to its normal position. The gun is now set. A 10 gopher will throw dirt on any object that it encounters in its runway, so that when an animal approaches the trap, it will throw dirt on the member 14, and the weight of this dirt will cause the member to move 15 downwardly, thus freeing it from the hooked end of the rod 18, so that the spring 11 can project the hammer against the cartridge and explode the same and thus kill the animal. A number of holes 8' are 20 formed in the support 1 for the bolt 8, so that the bracket 7 can be adjusted in said support. This will permit the barrel to be adjusted for different kinds and sizes of animals. As will be seen, the member 14 is 25 the first part of the trap that the animal encounters, so that it is this member that the animal will throw dirt upon.

Attention is called to the fact that the roller 17 is placed below and in front of the 30 pivot 15 of the trigger plate which helps the plate to snap off the hook when the plate is pushed downwardly. The bolt 18' acts to limit the upward movement of the rod 18, so that it will not move upwardly when the 35 trigger plate 14 is depressed, and it also limits the movement of said rod when the trap is inverted to set the same.

It is thought from the foregoing descrip-

tion that the advantages and novel features 40 of our invention will be readily apparent.

We desire it to be understood that we 45 may make changes in the construction and in the combination and arrangement of the several parts, provided that such changes fall within the scope of the appended claims. 45

What we claim is:—

1. A trap gun comprising a supporting structure, a barrel having one end pivoted to the same, means adjacent the other end of the barrel for limiting its swinging movement, a trigger pivoted to the structure, a spring for projecting the trigger, a pedal-like member at the front end of the structure and adapted to be depressed by an object striking the same, and means for holding the hammer in cocked position when the member is in raised position. 50

2. A trap gun comprising a channel-shaped supporting member; a leg pivoted to the rear end of the same, a bracket pivoted to the forward part of the member, a barrel having its forward end fastened to the bracket, a support against which the rear end of the barrel rests, a spring actuated hammer carried by the rear end of the supporting member and adapted to explode a cartridge placed in the barrel, a pedal-like member pivoted to the forward end of the supporting member, and a rod fastened to the hammer and having a hooked end for 60 engaging a part of the pedal-like member. 65

In testimony whereof we affix our signatures.

FRED R. SIMON.
ALBERT A. SIMON.
